Primary Examiner — Elizabeth J Oswecki(74) *Attorney, Agent, or Firm* — Charles E. Baxley(57) **CLAIM**

I claim the mount for a mailbox, as shown and described.

DESCRIPTION

FIG. 1 is a front, downwards, right perspective view of a mount for a mailbox showing my new design;

FIG. 2 is front, upwards, right perspective view thereof, shown in a used condition with a post shown in broken lines;

FIG. 3 is a left elevation view thereof, the right elevation view being a mirror image of the left elevation view;

FIG. 4 is a front elevation view thereof;

FIG. 5 is a rear elevation view thereof;

FIG. 6 is a top plan view thereof; and,

FIG. 7 is a bottom plan view thereof.

The post shown in broken lines form no part of the claimed design.
